(57) **CLAIM**

The ornamental design for an under shelf basket, as shown and described.

DESCRIPTION

FIG. 1 is a top, front, right side perspective view of an under shelf basket, showing my new design;
FIG. 2 is a bottom, rear, left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view showing the under shelf basket with its hanging bars in full extended state;
FIG. 10 is an enlarged view of portion 10 in FIG. 1;
FIG. 11 is an enlarged view of portion 11 in FIG. 1; and,
FIG. 12 is an enlarged view of portion 12 in FIG. 2.
The unevenly dashed broken lines define the boundaries of enlarged views and form no part of the claimed design.

1 Claim, 12 Drawing Sheets
